UNITED STATES PATENT OFFICE.

ORAN LILJEGVEST AND SAMUEL DURANT, OF WAUSAU, WISCONSIN.

DESIGN FOR A CRANK-ARM REPAIR-TIP.

SPECIFICATION forming part of Design No. 33,024, dated July 31, 1900.

Application filed June 23, 1900. Serial No. 21,385. Term of patent 14 years.

To all whom it may concern:

Be it known that we, ORAN LILJEGVEST and SAMUEL DURANT, citizens of the United States, residing at Wausau, in the county of Marathon and State of Wisconsin, have produced a new and original Design for a Crank-Arm Repair-Tip; and we do hereby declare the following to be a full, clear, and exact description of the invention, such as will enable others skilled in the art to which it appertains to make and use the same.

Our invention relates to a bicycle crank attachment; and it consists, essentially, of the design for a repair-tip for a broken crank-arm, substantially as shown in the accompanying drawings.

In the accompanying drawings, which illustrate our design, Figure 1 is a side view. Fig. 2 is a longitudinal section taken on the line

2 2 in Fig. 1. Fig. 3 is an end view; and Fig. 4 is also an end view, but looking at the opposite end of the device.

The essential characteristics of the design are the hollow or socket-like stem portion A, the flattened annular boss A°, and the oblong recess A' in the base of the hollow stem or socket-like stem portion A.

What we claim is—

The design for a crank-arm repair-tip substantially as herein shown and described. 30

In testimony whereof we affix our signatures in presence of two witnesses.

ORAN LILJEGVEST.
SAMUEL DURANT.
